LOCOMOTIVE BOILER

Bert E. Larson, Park Ridge, Ill., assignor to Locomotive Firebox Company, Chicago, Ill., a corporation of Delaware

Application April 7, 1941, Serial No. 387,255

2 Claims. (Cl. 122—68)

This invention relates to improvements in locomotive boilers and it consists of the matters hereinafter described and more particularly pointed out in the appended claims. The invention is more especially concerned with the construction in a locomotive boiler having a firebox equipped with a water steaming and circulating element that requires an elongated opening in the crown sheet for its installation. As an example of an element of this kind, mention is made of the well-known thermic syphons. Such an element includes a flat hollow staybolted body having an elongated and usually flanged top end discharge or outlet adapted to be secured in an elongated opening in the crown sheet and at least one tubular inlet neck adapted to be secured in an opening in another sheet of the firebox, below the crown sheet.

In the conventional type of locomotive boiler, crown staybolts are employed between the crown sheet of the firebox and that part of the wrapper or roof sheet thereabove and these bolts are generally much longer than the conventional staybolts employed between the side sheets of the firebox and the outer side sheets of the boiler shell. The top flange for the body has a width that is equal to the spacing between four transversely spaced rows of crown staybolts when said flange is fixed in the crown sheet.

Installing a thermic siphon in a firebox requires the making of an elongated opening in the crown sheet to receive the top end flange of the siphon and this opening generally extends longitudinally of the firebox. The standard practice in making such an elongated opening in the firebox is to dispose the center line thereof in line with one longitudinal row of crown staybolts within the area of said flange. The staybolts in this center row, as well as those in the rows at each side thereof, within the area of said opening, are then removed. When the siphon flange is disposed in the opening, the crown staybolts in the side rows in said area are replaced to again connect said flange to the wrapper or roof sheet. Heretofore no crown staybolts were employed or substituted for those removed from above the outlet opening of the siphon. This transferred the load to the crown staybolts connecting the flanges and the wrapper sheet and therefore in the replacement of such bolts, bolts of larger diameter were employed. The removal and omission of the center line of bolts also induces an additional load upon that area of the wrapper sheet above the siphon flange and between the side rows of bolts.

One of the objects of the invention is to provide a simple and efficient means for providing a connection between the outlet opening of the siphon and that part of the wrapper sheet thereabove and whereby said part of the wrapper sheet is better able to withstand internal boiler pressures.

A further object of the invention is to provide means for this purpose which includes a plurality of pivotal connections having axes disposed in a plane other than parallel with said means as a whole, whereby a limited lateral flexibility is present to accommodate some relative lateral movement between said part of the wrapper sheet and associated part of the crown sheet.

The above mentioned objects of the invention as well as others, together with the advantages thereof will more fully appear as the specification proceeds.

In the drawing:

Fig. 1 is a longitudinal vertical sectional view through the firebox end of a locomotive boiler embodying one form of the invention.

Fig. 2 is a transverse vertical detail sectional view through a part of the boiler and adjacent crown sheet part of the firebox on an enlarged scale as taken on the line 2—2 of Fig. 1.

Fig. 3 is a vertical detail sectional view as taken on the line 3—3 of Fig. 2.

Referring now in detail to that embodiment of the invention illustrated in Figs. 1, 2 and 3 of the drawing, 10 indicates as a whole the rear end part of the barrel or shell of a locomotive boiler and in which is located a firebox 11. The firebox 12 includes a crown sheet 13 which extends from the flue sheet 14 to the back sheet 15 of the firebox and which crown sheet merges at its sides into the side sheets 16 of the firebox, only one of which appears in Fig. 1. The bottom end part of the flue sheet merges into the front throat sheet 17.

17 indicates that part of the wrapper or roof sheet of the boiler above the crown sheet, 18 indicates the back sheet thereof and 19 indicates the outer front throat sheet. So-called crown staybolts 20 extend between and operatively connect the wrapper or roof sheet part 17 and the crown sheet. These bolts are disposed in rows extending longitudinally and transversely of the firebox.

The wrapper or roof sheet part 17 merges at its sides into the outside wrapper sheets (not shown) that are stayed to and cooperate with the side sheets 16 of the firebox to form the usual side water legs. The sheets 14 and 18 which are also staybolted together cooperate in form-

ing the back water leg 21 and the inner and outer throat sheets 16 and 19 which are also stay-bolted together, cooperate in forming the front water leg 22. All of said water legs are bottomed by a mud ring 23.

24 indicates as a whole, a water steaming and circulating element in the firebox and which element in this instance is illustrated as one of the well-known thermic siphons. Such a siphon comprises a flat hollow body disposed in an upright position in the firebox and generally extends longitudinally of the firebox.

The body of the siphon includes spaced side walls 25-25 and front and rear end walls 26 and 26a respectively. The side walls are connected together by longitudinal rows of staybolts 25a. The top end of the side walls and the front and rear end walls are formed as a laterally extending flange 27 that extends entirely about the top end of the body and said side walls are connected to said flange by a rounded corner 28 arranged in a plane above the topmost row of staybolts 25a. The flange mentioned defines the discharge or outlet of the siphon and through which water passes from the body of the siphon into the steam and water space of the boiler above the crown sheet.

The bottom of said body is closed by a bulged portion 29 that extends in a downward and forward direction in the firebox and terminates in a tubular inlet neck 29a that opens through the inside throat sheet 16 of the firebox so as to take in or receive boiler water from the front throat.

When only one of the siphons described is to be installed in a firebox, an elongated opening 28a is formed longitudinally in the firebox crown sheet of a shape and area corresponding to that of the siphon flange 27. When more than one siphon is to be installed in the firebox, usually a separate opening is made for each one of said siphons. In Fig. 2 only the sides of such openings are shown.

As before pointed out, the opening 28a is of a width substantially the same as the spacing between the centers of the crown staybolts 20 in four laterally spaced rows thereof. In producing said opening, its center line is disposed in the longitudinal plane of the center row of crown staybolts 20 in the crown sheet. Thus owing to the width of said flange 27, three rows of crown staybolts 20 are removed from the crown sheet within the area of said opening and this disposes the edge of said opening midway between adjacent rows of crown staybolts and disposes the planes of the rows of such bolts on each side of said center row about midway between the edges of the side portions of the flange.

In applying certain ones of the staybolts 25a in the top row thereof in the siphon body, near the flange 27, I pass certain ones through the sleeve 30 of a link member 31 that is positioned in the outlet opening of the siphon body. The ends of these staybolts are then upset in the usual manner. Thus each link member 31 has a connection with its associated one of said staybolts 25a of the siphon body.

A bifurcated bottom end of a clevis member 32 straddles the top end of a link member 31 and has a pivotal connection therewith as by means of a pin 33, the axis of the pin in this instance extending transversely of the firebox. The closed top end crotch of the clevis member has threaded thereinto the bottom end of a bolt-like rod 34

and the bottom extremity thereof may be upset as at 35 to hold this end of the bolt in place in the clevis.

The top end of said bolt-like rod 34 is made to have a so-called universal joint connection 36 with the wrapper or roof sheet. Said universal joint connection is not described in detail herein as its construction is well known. Instead of the universal joint connection mentioned, one of the so-called rigid type may be employed.

In installing the siphon, it will have attached thereto the link members 31, the clevises 32 and the bolt members 34, the connection for the top end of said bolt members with the wrapper sheet being made from outside of the wrapper sheet. Also in the installation of the siphons, a row of staybolts 37 is employed to connect each side portion of the flange 27 of the siphon body to the wrapper sheet.

It is apparent that by means of the construction described, the top end of the siphon is connected to that part of the wrapper sheet 17 thereabove so as to provide a mutuality of support. Therefore this part of the wrapper sheet is braced from the siphon against internal boiler pressure. Also the top end of the siphon is braced against depression and lateral spreading due to said pressure. By reason of the provision of the pivotal connections mentioned, the crown sheet may have a relative lateral movement with respect to the wrapper sheet within practical limits.

While in describing the invention, I have referred in detail to the form, construction and arrangement of the parts involved, the same is to be considered only in the illustrative sense so that I do not wish to be limited thereto except as may be specifically set forth in the appended claims.

40 I claim as my invention:

1. A locomotive boiler embodying therein a wrapper sheet, a firebox in said boiler including a crown sheet spaced below said wrapper sheet, a hollow water steaming and circulating element in the firebox having an end opening through the crown sheet so as to discharge water into the boiler space above the crown sheet, staybolts connecting opposed portions of said end of said element, a member having a connection with one of said bolts and extending upwardly therefrom, a clevis-like member having a pivotal connection with the first mentioned member, and means operatively connecting said clevis member with said wrapper sheet.

55 2. A locomotive boiler embodying therein a wrapper sheet, a firebox in said boiler including a crown sheet spaced below said wrapper sheet, a thermic siphon in the firebox having an end opening through the crown sheet so as to discharge water into the boiler spaced above the crown sheet, means extending between opposed portions of said end of said element, a link member connected to said means and extending upwardly therefrom, a bolt member depending from said wrapper sheet toward the crown sheet and having a clevis at its lower end and a pivot pin connecting the link member with the clevis, the pivot pin extending transversely of the thermic siphon whereby limited longitudinal and vertical movements between the siphon and the wrapper sheet are permitted.

BERT E. LARSON.
